UNITED STATES PATENT OFFICE.

GUSTAVE LEBRUN AND FERNAND CORNAILLE, OF PARIS, FRANCE.

APPARATUS FOR PRODUCING ACETYLENE GAS.

SPECIFICATION forming part of Letters Patent No. 595,816, dated December 21, 1897.

Application filed January 9, 1897. Serial No. 618,541. (No model.) Patented in France June 17, 1896, No. 257,301.

To all whom it may concern:

Be it known that we, GUSTAVE LEBRUN and FERNAND CORNAILLE, of the city of Paris, France, have invented Apparatus for Producing Acetylene Gas, (for which we have obtained Letters Patent in France for fifteen years, dated June 17, 1896, No. 257,301,) of which the following is a full, clear, and exact description.

Our invention relates to apparatus for producing gas, and has for its object to produce gas by bringing together two gas-producing elements and regulating such mixing or bringing together in a suitable manner.

To this end our invention consists in the construction hereinafter set forth and claimed.

Our invention will be understood by referring to the accompanying drawings, in which—

Figure 1 is a front elevation of an apparatus embodying our invention. Fig. 2 is a plan view thereof. Fig. 3 is a longitudinal section on line 33 of Fig. 1. Fig. 4 is a sectional elevation of a modified form of our apparatus. Fig. 5 is a side elevation of the bucket-chain-elevator apparatus for raising water.

The apparatus shown in Fig. 1 consists of a generator having a casing *a*, provided with manholes *d d*, closing openings *b c* in the casing. A shaft *h* projects into the casing opposite the aperture *b* and rests in a bearing *i*. This shaft *h* supports a perforated drum *e*, which contains the carbide. The drum *e* has a hollow axis *g*, fitting on the shaft *h*, so that the drum *e* can be slid onto the shaft *h* through the aperture *b*. The drum *e* contains calcium carbide and is provided with a lug *e'*, which is adapted to coöperate with an arm *h'* on the shaft *h*, so that the said shaft and drum may be coupled, whereby the drum may be driven by the shaft. The shaft *h* is provided with a wheel *k*, which is driven from a motor *l* by a band *m*. A pipe *r* leads from the generator *a* to the gas-holder or gasometer *u*. This pipe is provided with a cock *r'*, a gas cooling and condensing coil *r''*, and a receiver *v*, provided with a purge-cock *v'*. A standard *p'* carries at its upper end a reservoir *p* for containing water. Leading from the reservoir *p* is a pipe *n*, which leads into the generator-casing *a*, terminates over the revolving drum *e*, and has interpolated in its length a cock *o'* and a regu-

lator *o*, which regulator is shown in the present instance as a small pipe of proper size to allow just a sufficient quantity of water to pass, which pipe may be, as shown, in the form of a sight-feed regulator. A small pipe *q* rises from the receiver *v* and conveys gas into the water-reservoir *p*, which gas will force water out of the reservoir *p* into the generator *a* through the pipe *n*, it being understood that the reservoir *p* is a closed vessel except where it receives the pipes *q* and *n*, and consequently any admission of gas into the said reservoir by the pipe *p* will result in a corresponding outflow of water through the pipe *n* when the cock *o'* is open. A valve *s* in the pipe *q* regulates the flow of gas therethrough, the said valve being controlled by a valve-arm *s'*, resting on a spring *s''*, and provided with a weighted handle *s''*, perforated for the passage of a cord *u'*, which is secured to the gasometer or gas-reservoir *u*, and passes thence over pulleys *u''*, and is provided at its lower end with a weight *t* and a stop *t'*, which is adapted to come against the handle *s''* of the lever *s'*, so that when the gasometer *u* has descended far enough to bring the stop *t'* against the weighted handle *s''* the said stop will raise the arm *s'* and open the valve *s*, and when the gasometer rises the weight will be correspondingly lowered and the weighted handle *s''* will bear the lever *s'* down, thus closing the valve *s* and shutting off the supply of gas through the pipe *q* to the reservoir *p*. The outlet-pipe *x* leads from the gas-reservoir to the street or service pipe *x'*. The generator is likewise provided with an outlet-pipe or escape-cock *a'* for allowing the escape of mixed air and gas at the commencement of the operation.

The operation of the apparatus is as follows: The stop-cocks *r' o'* being closed and the air-escape cock *a'* of the generator open the cage *e*, filled with calcium carbide, is placed in position, the tray *f* emptied, if necessary, and the vessel *p* filled with water and closed. The covers *d* having been closed and stop-cocks *r' o'* opened the motor *l* is set in motion and the gas-holder being in its lowermost position the cock *s* is open, and the gas generated by the first admission of water to the generator passes to water-reservoir *p* to force water out of the reservoir onto the calcium carbide contained in the revolving drum.

When the air has been expelled from the generator, the cock α' is closed and the gas generated is delivered to the gas-holder. When the gasometer rises sufficiently to 5 lower the weight and stop t' to close cock s , the gas is shut off from reservoir p and the supply of water to the generator ceases. As the carbid receives no more water and is freed by the rotation of the drum of the 10 reservoir due to wet lime which falls into the tray f , the production of gas entirely ceases until the gas-holder descends and allows cock s to be opened by weight t , and so on until the charge of carbid is completely exhausted.

15 In the foregoing arrangement the water is supplied by the gas-pressure to the calcium carbid, but it may be supplied by a pump, or by a bucket-elevator, as shown in Figs. 4 and 5, driven from a wheel y , fast on the 20 motor-driven shaft h , by a chain z running on said wheel and a wheel 1 upon the axis of one of the drums 2 of the endless chain 3 of buckets 4, which raise the water contained in a tank 5 and discharge it into a funnel 25 6, carried by the standard 7, and connected with a pipe 8, from which the water is delivered by the pipe n onto the calcium carbid contained in drum e , any water in excess being returned by the overflow-pipe 9 to tank 30 5. The acetylene gas produced in the generator passes out through pipe r to the gas-holder u and raises the same, the motion of drum e and the supply of water being simultaneously arrested by a cranked rod 10 being 35 brought by the rise of the gas-holder u into engagement with the "fly" of the motor when the gas-holder reaches its highest point. The water then ceases to flow onto the carbid and the production of gas becomes momentarily 40 interrupted, but is resumed when the gas-holder descends, the fly then being released, the motor restarting the drum containing the calcium carbid and the pump or elevator.

Any suitable kind of motor may be employed

to drive the revolving drum e and water-elevator 3.

What we claim, and desire to secure by Letters Patent, is—

1. In the herein-described apparatus for producing acetylene gas, the combination 50 with the generator, of a closed water chamber or reservoir placed at a higher level than the generator and connected at its upper part by a pipe with the gas-discharge pipe from the generator so as to render the flow of water 55 dependent on the gaseous pressure in the water-chamber, a gas-holder, a pipe leading from the generator to the holder, a valve actuated by the gas-holder so as to arrest the admission of gas and consequently the supply 60 of water to the generator when the holder rises and a conduit connecting the water-chamber and the generator, as described.

2. In an apparatus for making acetylene gas, the combination of a revolving perforated drum or cage containing calcium carbid, means for removing the gas as generated, a gas-holder for receiving the gas, means for supplying liquid to the perforated cage, comprising a closed water-chamber, a pipe 70 connecting the water-chamber with the generator, a pipe connecting the water-chamber and gas-holder whereby gas-pressure from the gas-holder may be introduced into the water-chamber to force water therefrom to 75 the generator, and means for controlling the flow of gas through the said pipe controlled by the movement of the gas-holder, substantially as described and for the purposes set forth.

The foregoing specification of our apparatus for producing acetylene gas signed by us this 19th day of December, 1896.

GUSTAVE LEBRUN.
FERNAND CORNAILLE.
